KEY OPERATED ELECTRIC SWITCH

William E. Brown, Anderson, Ind., assignor to
General Motors Corporation, Detroit, Mich., a
corporation of Delaware

Application: March 20, 1951, Serial No. 216,587

2 Claims. (Cl. 200—4)

1

This invention relates to key operated electric switches, for use on motor vehicles and more particularly to a plurality of switches for controlling the ignition, starter, and other electrical circuits of the motor vehicle.

An object of the present invention is to provide a key operated electric switch having a plurality of control members in which a key is used to turn all of the control members simultaneously in one direction to complete the ignition circuit and when the key is pushed in longitudinally a starter control switch is actuated to complete the starter circuit, the said starter motor control switch being automatically returned to its non-contacting position as soon as the operating force is released.

The construction and arrangement of the stationary contacts and a pair of movable contactors, one of which drives the other, are such that when both contactors are rotated in one direction by a manually operated key to the limit of its movement in said one direction of rotation, the ignition circuit of the motor vehicle is closed, and when the key is pushed inwardly one of the contactors is moved longitudinally a predetermined distance the starter circuit of the motor vehicle is closed, and as soon as the pushing force is released the longitudinal movable contactor is returned to a position with respect to the stationary contacts wherein the starting circuit is broken while the ignition switch remains closed, the movable contactors remaining in those positions until they are rotated therefrom by turning of the key in the opposite direction.

Further objects and advantages of the present invention will be apparent from the following description, reference being had to the accompanying drawings wherein a preferred embodiment of the present invention is clearly shown.

In the drawings:

Fig. 1 is a side view of the lock and switch structure embodying the present invention.

Figs. 2 and 3 are front and rear views, respectively, of the lock and switch structure, and looking in the direction of arrows 2 and 3, respectively.

Fig. 4 is a sectional view taken on line 4—4 of Fig. 2.

Figs. 5 through 9 are sectional views, respectively, taken on lines 5—5, 6—6, 7—7, 8—8 and 9—9 of Fig. 4.

The combined lock and switch elements of the device illustrated herein are enclosed within a housing 20 formed by a die casting operation. The housing has a cylindrical front portion 21

and an enlarged cylindrical rear portion 22. The forward end of the front portion 21 is provided with a reduced portion 24 having external threads. The reduced portion 24 provides a shoulder which is adapted to abut the marginal wall of an opening in a support or dashboard of an automotive vehicle, not shown. The reduced portion is provided with a lug which registers with a notch in the opening of the support to prevent the housing from turning with respect to the support. The threaded portion of the front portion is adapted to extend through the opening in the support and receives a circular member, not shown, which is screw threaded on the threads which cover the end surface of the front portion 21 and for securing the casing to the support.

Since the housing is formed by a die casting operation the rear enlarged portion 22 is counterbored to provide an annular flange 30, a shoulder 31 and a bore 32 having bottom wall 33 provided with a plurality of raised retaining bosses 34 arranged in a circular row on the wall 33.

The front portion 21 is formed with a main bore 35 which is counterbored at the front end to form a recess 36 and a shoulder 37 and at the rear end to form a bore 38 and a shoulder 39 with the bore communicating with the bore 32. The open end of the portion 21 is provided with a notch 40 for admitting light rays to the recess 36. The bore 35 is interrupted by a groove 41, Fig. 9, extending inwardly from the shoulder 37 and terminating short of the shoulder 39.

35 A lock cylinder 45 of the customary type having tumblers which project a locking bar 46 radially from the cylinder to engage a groove 47 formed in the main bore 35. The tumblers are retractable upon the insertion of a proper key 48 whereupon the locking bar 46 is retracted from the groove 47 to free the cylinder for rotation. The cylinder is removably secured in position within the bore 35 by a U-shaped member 50 (Fig. 8) having its arms extending in an arcuated slot 51 formed on the periphery of lock cylinder 45. The member 50 is urged outwardly by a spring 52 behind the shoulder 39 and thereby secures the lock cylinder against withdrawal.

A driven member 55 of molded insulating material or plastic is inserted in the mouth of the enlarged cylindrical portion 22. The member 55 has a reduced cylindrical portion 56 which is adapted to rotate and slide longitudinally within the bore 38 by movement of the lock cylinder 45. The lock cylinder 45 has a non-rounded exten-

57 which fits into a corresponding recess formed with the cylindrical portion 56.

An apertured contact carrier 60 of insulating material is mounted on the driven member 55 and is arranged to rotate with the latter. The member 55 has flats formed on its periphery which have a sliding fit with corresponding flat surfaces formed in the interior of an aperture provided by the carrier 60. The rotary movement of the carrier 60 is limited by a projection 61 formed integral with the housing 20, see Figs. 4 and 7, which projects into a slot 62, formed on the periphery of the carrier 60. The rear face of the contact carrier 60 is provided with a circular row of spaced recesses 63 to receive the bosses 34 to hold yieldingly the carrier 60 in various positions. The front face of the carrier 60 is formed with a series of spaced pockets 64 in which project arms 65 of a ring type bridging member 66 to drive same. The front face of the carrier 60 has spaced pockets 67 to receive coiled springs 68. One end of each spring rests against the bottom of the respective pocket 67 while the other end seats in a depression 70 of the bridging member to urge the bridging member to the right and the carrier 60 to the left as viewed in Fig. 4. The bridging member 66 is provided with three of these depressions to provide spherical contacts.

The enlarged portion of the driven member 55 is provided with two aligned bores the inner one being smaller in diameter than the outer. The inner bore seats one end of a rod 71 embedded therein while the other end projects through and beyond the bridging member 66. The rod 71 has an annular groove to receive a retainer 72 furnished with a radial slot to permit assembly of the retainer with the rod 71. A relative weak compression spring 73, a washer 74 and a bridging member 75 are interposed between the retainer 72 and the bottom of the enlarged bore in the driving member 55 one end of the spring 73 being seated on the bottom of the large bore and the other end seating against the washer 74.

A sub-assembly of conductor plates and stationary contact terminals for closing the open end of the enlarged portion 22 comprises a body 80 of insulating material having an extension 80a provided with a counterbored recess having three different diameters to provide shoulders 81 and 82. The smaller bore receiving the end of the rod 71 to guide same in straight line axial movements. The shoulder 81 forms a seat for one end of a relatively stiff coiled compression spring 83 while the other end of the spring engages the retainer 72 that accidental removal of the retainer is substantially prevented by the spring 83. Since the spring 83 is under compression and has a greater biasing force than the spring 73, the rod 71 is urged to the left as viewed in Fig. 4 to hold normally the enlarged portion of the driving member 55 against the bottom wall 33.

A plurality of headed rivets are carried by the body 80 the heads of which form stationary contacts 85, 86, 87, 88 and 89 see Fig. 5. The heads of contacts 85, 86 and 87 are flush with the inner face of the body 80 while the heads 88 and 89 extend a short distance beyond the inner face of body. The shank of the rivets extend through the body and are attached to terminal plates. Referring to Fig. 3 the stationary contacts are connected to conducting plates in the following manner; terminals 85 and 88 to a battery plate 90 which is common to the ignition, starting, and accessory circuits; terminal 86 to ignition plate 91, 87 to gas or accessory plate 92, and terminal 75

89 to solenoid plate 93. The six shallow depressions 63 in the surface of the carrier cooperate with the bosses 34 to hold yieldingly the carrier 60 in the various positions of the switch.

5 Before the body is assembled with the enlarged portion of the body, a gasket 95 is placed on the shoulder 31. At suitable places the flange 30 is bent over against the rear face of the body 80 to hold firmly the gasket 95 and body 80 against the shoulder 31. When the closure 80 is secured in position, the spring 83 is in a highly compressed state to hold the driven member against the bottom wall 33. The springs 68 are also in a compressed state to urge the bridging member 66 to the right against the body so that contact bosses 70 bear against the bottom wall 33.

20 The operation of the switch is as follows: When the switch is in the locked "Off" position the bridging member 66 with its spherical contact portion 70, represented by letters A, B and C in Fig. 3, are out of engagement with stationary contacts 85, 86 and 87 and the bridging member 75 is urged by spring 83 out of engagement with contacts 88 and 89. While in the locked position the lock casing cannot move longitudinally to close the starter circuit as a projection 100 on lock cylinder head 45a abuts the shoulder 37. When the proper key 48 is inserted in the slot 101 provided by the cylinder 45 the locking bar 46 is removed from slot 47 to free the cylinder 45. When the key is turned a certain angular distance in a counterclockwise direction as viewed in Fig. 3, or clockwise as viewed in Fig. 9, the projection 100 registers with slot 41 and the points A, B and C will be in positions to engage the contacts 85, 86 and 87 associated respectively with plates 90, 91 and 92 to complete the ignition circuit. When in this particular position the shoulder 62a of slots 62 will abut projection 61 to align lug 100 with slot 41 thus permitting the lock cylinders if desired to be pushed in until head 45a engages the shoulder 37. When this happens the spring 73 will be compressed to hold firmly the contact 75 in engagement with the terminals 88 and 89 to complete the starting motor circuit. With the inward movement of the carrier 60 the stiff spring 83 will be further compressed between the shoulder 81 and the retainer 72. When the pushing force is released the spring 83 will expand and automatically return the carrier 60 quickly to its normal position to separate the contact 75 from contacts 88 and 89 to open the starting motor circuit. When the key is turned in the clockwise direction from the "off" position, Fig. 3, the shoulder 62b will engage the lug 61 causing the bridging member depressed contact portions A and C to engage contacts 85 and 87 to connect the gas gage or accessory lights in a circuit. When the lock cylinder is in this position inward movement of same is prevented as the projection 100 is out of registry with groove 41, thus the starter circuit cannot be switched on in this position.

55 When it is required to remove the lock cylinder 45 from the housing, it is necessary to move the cylinder to the accessory position of the switch, and it is merely necessary to use a suitable tool insertable in the opening 53 for depressing the retainer 50 inwardly to free it from the shoulder 39 to permit outward movement of the plug.

60 While the embodiment of the present invention as herein disclosed, constitutes a preferred form, it is to be understood that other forms might be adopted.

What is claimed is as follows:

1. A combined ignition and starter comprising, a lock and switch housing, a lock cylinder supported for rotating and longitudinal movement in the housing; a closure for the housing having a guide passage; a driven member of insulating material coupled with the lock cylinder; a pin having one end fixed to the driven member and having the other end fitting into the guide passage for guiding the driven member in a straight line; a removable abutment carried by the pin; insulated ignition terminals and a pair of insulated starter terminals carried by the closure; a bridging member about the pin; a spring for holding the bridging member against the abutment and for maintaining the coupled relation between the driven member and the lock cylinder; a carrier of insulating material driven by the driven member; a contact plate carried by the carrier and engageable with the ignition terminals upon rotary motion of the lock cylinder; a second spring disposed between the closure and the abutment for resisting axial movement of the driven member in one direction; and provision provided by the lock cylinder and the housing for permitting axial movement of the lock cylinder and driven member for actuating the bridging member into engagement with the starter terminal only when the contact plate engages the ignition terminals.

2. A key operated switch comprising, a housing; a lock cylinder supported for rotary and axial movement within the housing and operated be-

tween a locked and unlocked position; a closure for the housing having a guide passage formed therein; a pair of insulated terminals carried by the closure; an insulating member coupled with the lock cylinder within housing; a rod having one end fixed to the member and having the other end fitting into the passage and forming a guide therefor; a detachable abutment carried by the rod; a bridging member surrounding the rod; a compression spring disposed between the bridging member and the member for urging the bridging member against the abutment and for maintaining the coupled relation between the lock cylinder and the member; resilient means disposed between the abutment and the closure for resisting axial movement of the member and the lock cylinder, said lock cylinder and member being axially movable in the unlocked position against the force of the resilient means to move the bridging member into contact engagement with the terminals.
